UNITED STATES PATENT OFFICE.

WILLIAM A. BOND, OF LYNN, MASSACHUSETTS.

SOLE-EDGE-TRIMMING TOOL.

SPECIFICATION forming part of Letters Patent No. 375,334, dated December 27, 1887.

Application filed December 16, 1886. Serial No. 221,763. (No model.)

To all whom it may concern:

Be it known that I, WILLIAM A. BOND, of Lynn, in the county of Essex and Commonwealth of Massachusetts, have invented certain Improvements in Sole-Edge-Trimming Tools, of which the following, taken in connection with the accompanying drawings, is a specification.

This invention relates to improvements in edge-trimming tools, and the nature thereof is fully described and specifically claimed hereinafter.

Referring to the drawings, Figure 1 is a front elevation of the combined implement. Fig. 2 is a sectional elevation on line α α of Fig. 1. Fig. 3 is a front side elevation of the rand-cutting knife detached. Fig. 4 is an edge view of the rand-cutting knife.

The edge-trimming tool A is of well-known construction, and is known in the trade as the "Bussell edge-trimming tool." It has cutting-edges a , and when rapidly revolved the sole-edge is held up to and pressed upon the edges a , which trim off the surface of the leather and impart to the edge-face of the sole a configuration counter to the shape of the cutting-edges, all of which is well understood by those skilled in the art of making shoes.

It is the object of this invention to provide means, combined with the said edge-trimming tool, that shall operate in the rand-crease and perform the operation called "randing"—that is, trimming the inner side and edge of the sole—the two operations, randing and edge-trimming, being performed at one and the same time. To this end I provide a knife-blank, B, composed of sheet metal, having radial arms e , each of which is provided with a cutting-edge, f , as shown in Fig. 3. Fig. 4 is an edge view of this cutter, and by reference thereto it will be seen that the cutting-edges f are formed diagonally across the arm, so as to be in a plane inclined relatively to the face of the cutter B. This cutter is combined with a shield or guard, E, which is also formed of sheet metal, and is chambered out to receive the cutter, as represented in Fig. 2. It will be observed that the shield E has its outer edge extended inward entirely over the end faces of the arms e , and it is also provided with openings h , constituting throats, to allow the chips taken off

by the cutters f to pass readily outward, and thus prevent the tool from choking up. The cutter and shield, being thus arranged, are combined with the edge-trimming tool, as shown in Fig. 2, the rear face of the edge-tool being chambered out to receive the cutter-blank B; and it also allows the arms e to be let into suitable grooves formed across the tool, as shown in Fig. 2. This arrangement brings the cutting faces or edges f in past the end or extreme corner of the cutting-face a , respectively, to the end that these two edges shall lap past each other and prevent the thin shavings from wedging in between the cutting-edges.

In operation this combined tool is revolved rapidly on a suitable arbor by means of any suitable mechanism. The machines now in the trade are known as the "Bussell Trimmer," being well adapted for this purpose, the tool being secured to the arbor by a suitable screw passing through the central hole, H, and into the end of the shaft or arbor. The shoe is then taken in hand and pressed upward against the tool, the edge of the guard E passes into the rand-crease, protects the upper-leather from being injured by the rand-knife, and further progress of the shoe upward brings the edge-face of the sole into contact with the cutting-faces a , which form and fashion the sole-edge, while at the same time the inclined faces f are cutting from the inner side and along the edge of the sole a chip called the "rand-chip," and is known as the process of randing. The amount or quantity to be taken from this portion of the sole is limited by the inclination of the cutting-faces f as the guard E reaches over the cutting-arms and presents a smooth non-cutting edge that, bearing upon the side of the sole, prevents the tool from traveling laterally across the edge of the sole. This is one of the most important and useful features of my invention. It allows the shoe to be removed away from the tool for inspection or other purpose, and again to be pressed upon the tool without liability or danger of trimming too much off as a rand-chip. It also secures a uniform rand-chip, and therefore leaves the sole in uniform style along the rand-crease. It will of course be understood that the shoe is manipulated by the workman in the usual

manner to bring all parts of the sole-edge into contact with the trimming-tool.

What I claim as of my invention, and desire to secure by Letters Patent, is—

5 In a combined sole-edge trimming and randing tool, the combination of the edge-trimming knives *a* and the rand-trimming knives *f*, and a circalarguard or shield overlapping the ends of the rand-trimming knives and having an

inner non-cutting edge adapted to bear against the surface of the sole, the guard being adapted to revolve with the trimming-knives, substantially as and for the purposes stated.

WILLIAM A. BOND.
